UNITED STATES PATENT OFFICE.

WALTER E. HASSAM, OF WORCESTER, MASSACHUSETTS, ASSIGNOR TO HASSAM PAVING COMPANY, OF WORCESTER, MASSACHUSETTS, A CORPORATION OF MASSACHUSETTS.

PAVEMENT.

1,275,165.

Specification of Letters Patent.

Patented Aug. 6, 1918.

Application filed January 17, 1914. Serial No. 812,681.

To all whom it may concern:

Be it known that I, WALTER E. HASSAM, a citizen of the United States, residing at Worcester, in the county of Worcester, and 5 State of Massachusetts, have invented a new and useful Pavement, of which the following is a specification.

This invention relates to a paving for streets and the like and to a structure which 10 can be used for other purposes, such as vertical walls and the like. This invention is an improvement over the invention of Charles W. Ross, on a pavement for which he has filed an application for United States Letters-Patent Serial No. 808,405, filed Dec. 23, 15 1913.

The principal objects of this invention are to provide a pavement or structure based on the idea represented in the above-mentioned application in which the wood pieces are located in the structure in such a way that they will form a firmer support and resist pressure more fully; also to provide a structure based on this idea which can be 20 laid with more exactness and brought to a level more easily and which will present comparatively few and small voids for the absorption of the binding material and at 25 the same time will be capable of being reinforced to prevent creeping.

Further objects and advantages of the invention will appear hereinafter.

Reference is to be had to the accompanying drawings in which: 30 Figure 1 is a transverse sectional view of a portion of a pavement constructed in accordance with this invention;

Fig. 2 is a plan of one layer or course of the pavement; and Fig 3 is a view similar to 40 Fig. 1 of a modification.

As stated in the above-mentioned application, an ordinary type of pavement widely used at the present time involves the employment of finely broken stone which can be obtained only in certain localities and which involves considerable expense, both 45 for the purchase thereof and for transportation, and that invention was designed for substituting for the broken stone a material, 50 namely wood, which can be obtained in many places at a much lower rate and which can be so laid in the pavement that it will last for indefinite periods.

In order to carry out this purpose and

also to provide the advantages above mentioned, instead of placing the wood pieces at random in the pavement, I place it all in one direction, that is, with its grain vertical. In this way the pressure on the pavement is taken by the grain of the wood and 55 also the straight surfaces of the wood come together so that the voids are reduced materially; moreover, the open grain end surfaces are fully and perfectly coated and protected before the binder comes into contact 60 with the split or side surfaces.

As a specific example of manufacture, the road which is to receive the pavement is first leveled off, or otherwise brought to a solid sub-grade of uniform cross section by 70 rolling, tamping or in any other way, and this produces a flat surface *a*. On this surface may be flowed a layer of binding material *b*. Either in this layer while still soft or on the surface *a* is placed a layer of 75 wood pieces *c*, these previously being first collected together with the grain parallel and formed in bundles which are indicated in Fig. 2. Each of these bundles is made up of a plurality of pieces of wood all sawed 80 or cut off the same length so that the ends lie flat in a plane and the thickness of the bundle is equal to the length of each individual piece. These bundles are made of 85 any desired shape and the pieces held firmly together so that the voids are small. All of

them are of the same thickness so that when these bundles are placed in position, the level of the grade is raised exactly the thickness of the bundles. Then the voids between the 90 bundles are preferably filled by introducing wooden blocks of the same length between them. The strings or wires *d* which tie the bundles together can be loosened or cut if desired so as to make the voids more uniform 95 throughout the whole mass. It will be understood, of course, that this layer can be rolled if desired to bring it still further to a level, but inasmuch as the surface *a* has previously been rolled, ordinarily this is not 100 necessary, the wood not being compressible of course. Moreover, as the wood is all located with the grain parallel, the rolling would not force the wooden particles nearer together.

If it is desired to reinforce the pavement to prevent creeping back and forth, a woven wire mesh fabric *e* is then placed over the

layer of wood. This can be of any desired size, about a three-quarter mesh being preferred.

It will be understood of course that the wooden pieces then, although all of the same length, are of various cross sections and as waste wood is employed wherever possible, it will be obvious that there is no regularity about the angles which the various blocks make with each other. On account of their being first collected in bundles and each bundle tied with a string or wire *d* after they are forced together, in the same way that kindling wood is bundled up, it will be seen that only small voids appear between the pieces and that the voids between the bundles themselves are partially filled.

In some cases I prefer to partially fill the voids still further by introducing pea stone, sawdust, or small fragments of wood on the surface of this layer of wooden blocks, and brushing it back and forth until it disappears into the voids. This step, however, can be omitted if desired.

The next step of the process consists in flushing the surface of this layer of wooden blocks with a grouting or binding material *f*, preferably a bituminous or asphaltic one, such as is now frequently employed for use on stone pavements, but a cementitious binding material, such as Portland cement, can be used in place of it. This is flooded over the entire surface of the wooden layer to such a thickness and such a degree of consistency that it will flow down between the wooden pieces and coat them so as to protect them from the action of the air and moisture when in use. This is first received on the sawed, flat, open-grain ends of the wood, and no matter how thin it is or how much or little flows down the sides of the wooden pieces, these ends are coated and sealed permanently. When the layer *b* of binding material is used, the lower ends are sealed just as surely.

It will be understood of course, that the entire pavement can consist of a single layer of the wooden blocks treated as above specified, but in the form shown in the drawings, the pavement is shown as comprising two layers, the second layer *c* being now applied on top of the soft binding material, some of which remains on the upper surface of the first layer. This layer of wood is of the same character as the first layer and is treated in the same way, preferably. The voids in this case are preferably filled, however, with pea stone *g*. This is spread over the wooden layer and raked along it so as to enter the voids and fill all those except the smallest ones, and a surplus is used so as to provide a wearing surface above the wood. This can then be rolled if desired and then a second layer *h* of binding material 65 is flushed over the surface for the same pur-

pose as the first layer. It will be understood that pea stones on this layer are used not only to fill in the voids, but also for forming a wearing surface above the top of the wooden layer and consequently they are spread over it to a thickness of perhaps half an inch before the binding material is applied. After the binding material hardens, a layer of sand can be spread over the top if desired, but the real wearing surface consists of the pea stones intermingled with the binding material. If only a single course of wood *c* is used as in Fig. 3 the pieces preferably are longer than those used for each of a plurality of layers, and the reinforcing is done by means of rods *i*.

In this way it will be seen that a solid and durable base is furnished for the pavement and that after the sub-grade is finished and rolled hard it may be unnecessary to roll it further in ordinary practice, although it can be rolled if desired. The filling of the voids between the pieces of the wood with small fragments of wood, sawdust, or pea stone adds to the rigidity of the pavement and reduces the amount of binding material necessary. The fact that the wooden blocks are arranged with their grain vertical with sawed ends on the top side, results in assuring that the ends of the grain in every case are thoroughly covered and sealed by the binding material and this is an important feature of this invention because it leaves nothing to chance, and the preservation of the wood is assured.

Variations of this method of procedure can be employed for similar purposes, for example, blocks of paving material can be made by a similar process except that they are not made on the pavement itself, and these blocks consisting of wood embedded in the binding material can be used for forming sidewalks and other pavements. Moreover, said blocks can be used for forming vertical walls and in fact the process can be carried out for the latter purpose for building the walls in position with the wooden blocks located therein in substantially the same way as has been described with reference to their use for pavements.

Although I have illustrated and described only a few applications of the invention and only a single method of carrying it out, I am aware of the fact that the invention can be used for other purposes and carried out with other changes in details without departing from the scope thereof as expressed in the claims.

Therefore, I do not wish to be limited in these respects, but what I do claim is,—

1. A pavement comprising a layer of pieces of wood, a reinforcement on the top of said layer, a second layer of pieces of wood on top of the first layer, and a binding material covering the open grain ends

of the wood and sealing the same and extending down into the voids through the pieces and through the reinforcement.

2. A pavement comprising a layer of 5 pieces of wood having the grain thereof vertical, a reinforcement on the top of said layer, a layer of paving material on top of the reinforcement, a binding material covering the open grain ends of said wood and 10 sealing the same and extending down into the voids between the pieces.

3. A pavement comprising a layer of pieces of wood having the grain thereof vertical, a reinforcement on the top of said

layer, a second layer of pieces of wood on 15 top of the first layer having the grain thereof vertical, and a binding material covering the open grain ends of said wood and sealing the same and extending down into the voids between the pieces.

In testimony whereof I have hereunto set my hand in the presence of two subscribing witnesses.

WALTER E. HASSAM.
